CLAIM

The ornamental design for a handle for a combined sealer, divider and dissector device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a claimed design, showing the claimed design in a first configuration;

FIG. 2 is a right side view of the claimed design shown in FIG. 1;

FIG. 3 is a left side view of the claimed design shown in FIG. 1;

FIG. 4 is a front view of the claimed design shown in FIG. 1;

FIG. 5 is a back view of the claimed design shown in FIG. 1;

FIG. 6 is a top view of the claimed design shown in FIG. 1;

FIG. 7 is a bottom view of the claimed design shown in FIG. 1;

FIG. 8 is a perspective view of the claimed design, showing the claimed design in a second configuration;

FIG. 9 is a right side view of the claimed design shown in FIG. 8;

FIG. 10 is a left side view of the claimed design shown in FIG. 8;

FIG. 11 is a front view of the claimed design shown in FIG. 8;

FIG. 12 is a back view of the claimed design shown in FIG. 8;

(Continued)

FIG. 13 is a top view of the claimed design shown in FIG. 8; and,

FIG. 14 is a bottom view of the claimed design shown in FIG. 8.

The figures illustrate a handle for a combined sealer, divider and dissector device. The colors in the claimed design illustrated in FIGS. 8-14 are Pantone 532C (RGB 29 3142), Pantone 285C (RGB 0 114 206), Pantone 11-4001 (RGB 237 241 255), and Pantone Cool Gray 5C (RGB 177 179 179).

Features shown in broken lines are for illustrative purposes only and form no part of the claimed design.
